FASTENER FOR WRIST WATCHES

Geyza Karlovszky, Budapest, Hungary

Application May 5, 1932, Serial No. 609,437
In Hungary June 1, 1931

3 Claims. (Cl. 24—3)

This invention relates to a fastening device for watches to be carried in the button hole of the coat lapel, especially for wrist watches provided with loops, in which device a button mounted on a shank is connected to the back of the watch, and the characteristic feature of the invention as compared with the known state of the art consists in that the button and the shank are fixed on a metal band which has hook shaped ends detachably engaging around the loops of the wrist watch, one of the hook shaped ends of this metal band being mounted on a hinge and having at its end a slot for the passage of the button shank which is screwed into a projection arranged in the middle of the metal band. According to the invention a locking element is hingedly connected to the other hook shaped end of the band, which is resilient, and serves for preventing the button shank from coming unscrewed.

The fastening device according to the invention presents the advantage that wrist watches provided with loops can thereby be easily converted by any inexperienced persons into watches for wearing in the button hole in a coat lapel, whereas hitherto only specially constructed so called button hole watches could be worn in the button hole of the coat lapel and were useless for any other purpose.

Several embodiments of the invention are illustrated by way of example in the accompanying drawing in which:—

Fig. 1 shows in elevation the rear side of a watch with hingedly connected two-part button mounted directly thereon.

Fig. 2 is a side elevation of Fig. 1.

Fig. 3 shows in elevation the rear side of a watch with strap for connecting the watch to the button.

Fig. 4 is a side elevation of Fig. 3.

Fig. 5 shows the button in the lapel button hole.

Fig. 6 shows the watch on the under side of the lapel.

According to Figs. 1 and 2 the shank 2 of a button is fixed on the rear side of a watch case 1. This shank carries a button 3 which consists of two hingedly connected parts 3, 3 foldable like a cup link and forming together a badge.

According to Figs. 3 and 4 any wrist watch may

be employed in that the elements 2, 3 are fixed on a metal band 5, 6, 7 which is detachably fixable on the loop extensions 4 of the watch. To one end 11 of the metal band a metal strip 7 is hingedly connected. The other end 6 of the metal band 5 is bent back and carries on its end 8 a hingedly mounted buckle 9. The extension 7 of the band is folded over into the position 7' indicated in dotted lines and threaded through the two loop-shaped extensions 4, 4 of the watch casing, the parts 5, 6 embracing one of the extensions 4 and the second extension coming between the parts 5, 7. On the middle portion 5 of the metal band a screw nut 12 is soldered, into which an extension 10 of the button shank is screwed, the parts 5, 7 being thus secured in their position. The buckle is then folded from the position 9', shown in dotted lines, into the position 9 in which the ends 9'' of the buckle embrace the button shank 2 and secure it against turning. The metal band portion 7 has at its end a slot 7' for the passage of the screw shank extension 10.

In Figs. 5 and 6 the lapel of the coat is designated by 16 and the button hole by 17.

I claim:—

1. A fastener for a wrist watch having loops on the case thereof, comprising a metal band, hook-shaped extensions on said band adapted to detachably engage said loops, and a button with shank on said metal band.

2. A fastening device as specified in claim 1, comprising in combination, one of said extensions being resilient, the other of said extensions being hingedly connected at one end to said band and having a slot at its other end for the passage of said button shank, and a screw threaded projection in the middle of said band adapted to engage the free end of said button shank.

3. A fastening device as specified in claim 1, comprising in combination, one of said extensions being resilient, the other of said extensions being hingedly connected at one end to said band and having a slot at its other end for the passage of said button shank, a screw threaded projection in the middle of said band adapted to engage the free end of said button shank, and a locking element on the end of said resilient hook-shaped extension adapted to prevent the unintentional unscrewing of said shank.
